COLLAPSIBLE CONTAINER

Abraham Stone, Brooklyn, N. Y.

Application December 29, 1932, Serial No. 649,388

1. Claim. (Cl. 229—41)

This invention relates to moth-proof containers in which clothing may be stored to protect the same, and has for an object to provide a container of this character which is so constructed as to effectively prevent the entrance of dust or insects and which is collapsible from a set-up condition to a flat compact condition.

Another object of the invention is the provision of a container of this character having a supporting structure for holding the walls of the casing in a normal box-like form and which is foldable or collapsible with the casing to a flat compact condition.

Still another object in view is the provision of a container of this character consisting of a pliable outer casing entirely sealed except for an opening at one end and which is provided with a relatively stiff supporting structure secured within the casing in a manner to support the walls thereof and to hold the same in its normal box-like form when in set-up condition, and which is foldable to a flat compact condition with the folding of the casing.

A further object is to provide a container of this character with handle members rigidly connected to the end walls thereof providing convenient means for carrying the same and which do not interfere with the collapsing of the container.

With these and other objects in view, the invention consists in certain novel features of construction and arrangement of parts which will be more fully described and claimed hereinafter.

In the accompanying drawing illustrating the invention

Figure 1 is a perspective view of the container showing, in dotted outline, the supporting structure within the container, and score lines on which the container is folded to a flat compact form;

Fig. 2 is a vertical sectional view on line 2—2 of Fig. 1;

Fig. 3 is a perspective view of the container in closed condition;

Fig. 4 is a side view of the container when collapsed;

Fig. 5 is an enlarged vertical sectional view on line 5—5 of Fig. 4, with certain of the folds spread apart to more clearly indicate the manner of folding the container;

Fig. 6 is a longitudinal sectional view of a portion of the container partly collapsed, on line 6—6 of Fig. 4;

Fig. 7 is a perspective view of a portion of the

top of the container showing the manner of rolling and securing said top to close the same.

Referring to the drawing illustrating the preferred embodiment of the invention, a moth-proof container 10 is provided which consists of a flexible casing 11 and a supporting structure 12 arranged within the casing. The casing 11 may be made of any suitable pliable material, such as tough paper or the like, which may have its seams secured together by any desired means, such as by an adhesive, to effectively seal the same against the entrance of dust or insects. The casing comprises a rectangular bottom wall 13 and rectangular side and end walls 14 and 15, and 16 and 17, the top or upper end 18 being open or without a cover or closure but which may be closed by collapsing the end walls 16 and 17 of the container inwardly on the vertical fold lines 19 and on the diagonal fold lines 20 and 21 until the side walls 14 and 15 meet at the top 20 which is then rolled or folded, as shown in Fig. 5, and secured in folded condition by clips 22, as shown in Fig. 7.

The supporting structure 12 is formed of relatively stiff material, such as cardboard or the like, which is sufficiently strong to support whatever clothing may be stored therein without undue strain or bulging of the side walls thereof.

This supporting structure comprises side walls 23 and 24, end walls 25 and 26, a bottom wall 27 which is hinged to the side wall 24, and a top wall 28 which is also hinged to the said side wall 24. The said walls may be joined together in any desired manner to provide a box conforming to the shape of the casing and which snugly fits within the casing so that the end and side walls thereof may be permanently secured to the corresponding end and side walls of the casing by an adhesive or other securing means.

The bottom wall 27 is of a size to snugly contact with the inner faces of the side and end walls of the supporting structure 12. In this manner the said bottom wall when in position on the bottom wall 13 of the casing, as shown in Fig. 2, operates to hold the said walls of the container and the casing extended. This wall is swingable from its bottom position to a vertical position against the side wall 24.

The top wall 28, which forms the lid for the supporting structure 12, is provided with depending flaps 29, 30 and 31. When the lid is closed, the end flaps 29 and 31 are positioned between the side wall 23 of the supporting structure 12 and the side wall 14 of the casing, while the intermediate flap 30 is positioned against the inner 55

face of the side wall 23, as shown in Fig. 2. The flaps being thus arranged, the lid 28 operates to hold the upper portion of the supporting structure and the casing in extended relation. The lid 28 being hingedly connected to the rear wall 24, as hereinbefore described, is swingable to a vertical position within the supporting structure against the bottom wall 27 when it is desired to collapse the container, as shown in Fig. 5.

10 Thus arranged, the supporting structure effectively reinforces the flexible walls of the casing and provides a container in which articles may be stored. The upper portion of the casing above the said supporting structure is adapted to be 15 folded, as hereinbefore described, to close the open end, thereby providing a substantially sealed container for the storage of clothing and for preserving the same against attack by insects.

When the container is not in use, it may be 20 readily folded or collapsed to a flat compact condition so that it will not take up the space it occupies when in set-up condition. To collapse the container, the bottom wall 27 and the top wall 28 are folded inwardly to vertical positions parallel to the side wall 24, after which the bottom wall 13 of the casing may be folded inwardly on the longitudinal fold lines 32 and the diagonal fold lines 33 and 34, whereby the said bottom wall will assume the folded position shown in Fig. 5. 25 With the folding of the said bottom wall, the portion of the side wall 23 of the supporting structure 12 and of the side wall 14 of the casing between the vertical fold lines 35 and 36, will move inwardly adjacent the collapsed top wall 28. At 30 the same time, the end walls 16 and 17 of the casing 11 and the end walls 25 and 26 of the supporting structure 12 will fold, as shown in Figs. 4, 5 and 6, with the end portions of the wall 14 of the casing and the end portions of the wall 23 formed by the fold lines 35 and 36, respectively.

When the casing and the supporting structure are completely collapsed, the upper portion of the casing above the supporting structure may be rolled upon itself, as shown clearly in Fig. 5.

Thus constructed, the end walls of the casing and supporting structure may be provided with handle members 37 rigidly affixed thereto to provide a convenient means for carrying the container and which do not interfere with the collapsing of the container. The said handle members 37 are affixed to the casing by means of cleats 38 which are folded against the inner face of the end walls of the supporting structure.

It is to be understood that the container may 15 be provided with any desired moth-repellent material which may be arranged within the supporting structure or impregnated in the wall thereof.

What I claim is:

In a collapsible container of the type having a 20 flexible outer casing opening at the top, a supporting container formed of relatively rigid material disposed in said casing and having side, end, top and bottom walls, the top and bottom walls being hinged to one of said side walls at the 25 top and bottom respectively so as to be swingable inwardly to collapse in parallel relation with said wall, the free end of said top wall being provided with means for releasably engaging both the inner and outer surfaces of the upper end of the 30 other side wall, said top, bottom, and side wall to which they are hinged and the end walls being uncreased and the other side wall being provided with two vertical fold lines one on each side of the center of said wall, so that the box may be 35 collapsed into a flat, compact form with the two end walls overlying the last-mentioned side wall.

ABRAHAM STONE.
